(57) **CLAIM**

The ornamental design for an operating element for a media preparation apparatus, as shown and described.

DESCRIPTION

The file of this patent contains at least one figure executed in color. Copies of this patent with color figures will be provided by the Office upon request and payment of the necessary fee.

FIG. 1 is a front view of an operating element for a media preparation apparatus showing the new design.

FIG. 2 is a rear view of the operating element for a media preparation apparatus of FIG. 1.

FIG. 3 is a left side view of the operating element for a media preparation apparatus of FIG. 1.

FIG. 4 is a right side view of the operating element for a media preparation apparatus of FIG. 1.

FIG. 5 is a top view of the operating element for a media preparation apparatus of FIG. 1; and,

FIG. 6 is a bottom view of the operating element for a media preparation apparatus of FIG. 1.

The drawing is lined for color.
